UNITED STATES PATENT OFFICE.

HENRY C. MILLER, JR., OF HAZLETON, PENNSYLVANIA, ASSIGNOR OF ONE-HALF TO PETER J. MILLER, OF HAZLETON, PENNSYLVANIA.

GRINDING OR POLISHING CONE.

SPECIFICATION forming part of Letters Patent No. 691,066, dated January 14, 1902.

Application filed May 10, 1901. Serial No. 59,663. (No model.)

To all whom it may concern.

Be it known that I, HENRY C. MILLER, Jr., a citizen of the United States, residing at Hazleton, in the county of Luzerne and State of Pennsylvania, have invented a new and useful Grinding or Polishing Cone, of which the following is a specification.

This invention relates to a grinding and polishing cone for treating or operating upon dental plates; and the object in view is to facilitate the finishing of dental plates which carry teeth by a simple and effective yielding cone structure of a particularly nature and economical and cheap character.

15 The invention consists in the construction and arrangement of the several parts, which will be more fully hereinafter described and claimed.

In the drawings, Figure 1 is a perspective view of a cone structure embodying the features of the invention. Fig. 2 is a longitudinal vertical section of the same shown applied to a rotatable portion of a dental lathe or analogous device. Fig. 3 is a transverse vertical section through the core end of the device. Fig. 4 is a detail elevation of one of the end covering devices. Fig. 5 is a plan view of a portion of the strip removably applied to the improved device and having an abrading-surface.

Similar numerals of reference are employed to indicate corresponding parts in the several views.

The improved device comprises a tubular core 1, of cork, and thereon is wound a strip 2, of sand or emery paper, the core being considerably less in length than the device as an entirety. The strip 2 is of the form shown by Fig. 5 and has one edge 3 straight and the opposite edge 4 obliquely cut, the strip gradually increasing in width to its maximum dimension in width from the extremity directly engaging the core to the outer end of the same, and consequently as the coiled laminæ are applied they gradually increase in projection from the inner end of the core and extend beyond successive adjacent edges, and thereby produce a conical hollow portion converging toward the core end. This construction provides a grinding or polishing device having the greater portion thereof flexible or freely

bendable, so as to conform and effectually operate on the surface against which it is brought to bear. Against the outer end of the core and the coiled strip 2 thereon a cardboard or other suitable cover 5 is applied and secured by any practicable means to keep the strip laminæ in close relation, and on the said cover is externally applied a disk head 6, which has an abrading-surface, as shown, 55 and is at times used for polishing or smoothing portions of the plate, if desired, and found necessary that such angular abrading-surface be employed. The cover 5 and head 6 have openings 7 in the center thereof, which align 60 with each other and coincide with the bore of the core 1.

The device is adapted to be applied to a lathe mandrel or screw, as shown by Fig. 2, the cork core setting up a tight frictional engagement with the end of said mandrel or screw to prevent the entire device from turning, and the direction of rotation of the mandrel or screw will be the same as the direction of winding of the strip. The mandrel or screw will be a 70 part of a lathe usually employed by dentists and driven either by foot or motive power, or if the device be used for other than dental operations any other suitable rotating device may be used for imparting motion to the cone. 75 After one exposed circumferential length becomes worn out it is removed to expose a new surface by uncoiling a suitable length of the strip, and this operation will be continued until the strip length has been completely exhausted. 80

The preferred use of the device is in connection with dental plates carrying teeth. After the impression of the mouth is taken the teeth are edged up and flasked, vulcanized, &c., and after vulcanization the plate is taken from the flask and washed. The plate will show more or less excess of rubber, which is taken off by a coarse file and the inside scraped after filing. There will be ridges 90 or scratches left in the plate, and the improved device is set in motion and the plate is brought to bear against the flexible or bendable portion thereof, so that a conformity will be had by the cone or improved device with 95 relation to the plate contour to remove said ridges or scratches, and after a short opera- 100

tion of this character the plate will be ready for the final polishing operation.

The improved device can be made in various sizes and will prove a valuable addition to the particular art to which it is specially adapted.

Having thus described the invention, what is claimed as new is—

1. A device of the class set forth, comprising a core, and a strip of abrading material wound thereon, the said strip having a straight edge and an oblique edge whereby one extremity of the device will be flexible or freely bendable to conform to the contour of the surface against which it is brought to bear.

2. A device of the class described, comprising a tubular cork core, an abrading-strip wound thereon and having one straight edge and an opposite oblique edge to regularly,

project the laminae of the strip successively 20 beyond each other to form a conical hollow in a greater portion of the device and provide the latter with a flexible or freely-bendable extremity, and means for holding the strip in wound condition until unwound to present a 25 new abrading-surface.

3. A device of the class set forth having a body composed of a wound strip of abrading material with the edges flush at one end and regularly projected beyond each other at the 30 opposite end to provide a flexible extremity.

In testimony that I claim the foregoing as my own I have hereto affixed my signature in the presence of two witnesses.

HENRY C. MILLER, JR.
